(57) CLAIM

The ornamental design for an orchid flower pot as shown and described.

DESCRIPTION

FIG. 1 is an isometric view of an orchid flower pot showing my new design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top plan view thereof; and,

FIG. 7 is a bottom plan view thereof.

The portions of the orchid flower pot shown in broken lines form no part of the claimed design. The outer dot-dash-dot broken lines define bounds of the claimed design and form no part thereof.

1 Claim, 7 Drawing Sheets
